UNITED STATES PATENT OFFICE

FRED M. MOORE, OF OAKLAND, CALIFORNIA, ASSIGNOR TO ECONOMY OIL SLOT PISTON COMPANY, OF RENO, NEVADA, A CORPORATION OF NEVADA

PISTON

Application filed February 18, 1929. Serial No. 340,785.

This invention relates to gas engine pistons and particularly represents improvements over the structure shown in my pending application for patent, Serial No. 320,592 filed November 20th, 1928.

5 The principal object of the present invention is to provide a piston constructed to attain the same ends as was the case with the previous one, namely to prevent what is commonly known as "oil pumping"; but which 10 is so arranged that such pumping is more positively prevented than was previously the case.

15 A further object of the invention is to produce a simple and inexpensive device and yet one which will be exceedingly effective for the purpose for which it is designed.

20 These objects I accomplish by means of such structure and relative arrangement of parts as will fully appear by a perusal of the following specification and claims.

25 In the drawings similar characters of reference indicate corresponding parts in the several views:

Fig. 1 is a fragmentary sectional elevation of a gas engine piston, associated with the necessary compression rings showing the piston on its "down" or suction stroke.

Fig. 2 is a similar view showing the piston 30 on its upward or compression stroke.

Fig. 3 is a fragmentary sectional plan taken on the line 3—3 of Fig. 2.

35 Referring now more particularly to the characters of reference on the drawings, the numeral 1 denotes the upper body portion of the piston in which the usual annular ring grooves 2 are cut, the skirt 3 below the upper portion and which has the wrist pin bearings 4 therein having air passages 5 of some sort 40 cut through just below the lowermost ring groove. This construction is standard in one form or another in almost all modern gas engine pistons and prevents the formation of a vacuum seal between the bottom of the skirt 45 and the ring grooves.

A small continuous annular groove 6 is cut in the land between the lowermost ring grooves, slots 7 being cut through from the interior of the piston at intervals to communicate with said groove. From the bottom of

each such slot intermediate its inner and outer ends a small bypass 8 connects with the top of the lowest ring groove 2 adjacent the back thereof, said bypass being drilled so as to have an outward slant from the slot to the groove. Somewhat larger openings 9 are drilled from the back of said lowest ring groove at the bottom straight through to the interior of the piston.

55 The theory of operation and function of the above features of construction is as follows:

60 On the downward movement of the piston during the suction stroke the pressure in the cylinder above the piston is considerably less than that in the interior of the piston, as will be evident; the latter pressure being substantially atmospheric. The compression rings 10 which frictionally engage the cylinder walls are relatively retarded in their 65 downward movement and their upper faces are consequently tightly engaged with the upper faces of the grooves, leaving clearance between their lower faces and the bottom of the grooves, as shown in Fig. 1.

70 With the provision of the slots 7 alone however, as in the previous construction, on the down-stroke of the piston the relatively great crank case pressure acts both through the slots 7 to the groove 6 and the upper outer edge A of the lower ring, and through the holes 9 to the lower ring groove and to the lower outer edge B of said ring.

75 Such pressures therefore act against any oil in their path (and which has collected back of and above the lower ring during the previous upstroke) and tend to force the oil upwardly rather than allowing the same to drain back into the crankcase through the openings 9, thus defeating the object it is desired to attain.

80 On the upward stroke of the piston, however, all oil collecting between the cylinder wall and groove 6, and back of the lower ring, will drain back to the interior of the piston by gravity provided the vacuum back of this oil is released or broken.

85 During this stroke, the setting of the rings is reversed from that previously set forth and the rings are clear of the tops of their grooves 90

and sealed against the bottom of the same, as shown in Fig. 2. To give this desired relief for the oil, the bypasses 8 are provided. These allow the vacuum pressure otherwise holding the oil sealed back of the lower ring to be broken by allowing the passage of air through the slots 7 and bypasses 8 to the top of the lower ring-groove, enabling the oil to flow by gravity both from behind the ring and from the groove 6 and slots 7, back into the interior of the piston.

The slots 7 are therefore drained of their oil with each upward movement of the piston so that they are always clear on the down stroke of the piston, thus providing the necessary vacuum break just above the lower ring and positively preventing oil pumping.

It will be of course understood that the clearance between the rings and grooves shown in the drawings has been exaggerated for the purposes of illustration. It is well known however that such clearance, no matter how small, inevitably exists and as such clearance increases with the age and wear of the motor the necessity for the non-pumping arrangement becomes of course greater.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

40. 1. A piston comprising a hollow body having spaced annular ring-grooves, an additional annular groove in the outer face of the land between adjacent ring-grooves, passages from said additional groove to the interior of the piston, and oil passage means from said passages intermediate their ends to the interior of the piston at a lower level therein, said passage means including the space between the back of the lower ring groove and the ring therein.
45. 2. A piston comprising a hollow body having spaced annular ring-grooves, an additional annular groove in the outer face of the land between adjacent ring-grooves, slots cut through from the interior of the piston and communicating with said additional groove, a bypass from each slot intermediate its ends to the top of the ring groove below; said ring groove having spaced openings 50 from the back thereof to the interior of the piston.

In testimony whereof I affix my signature.
FRED M. MOORE.
